UNITED STATES PATENT OFFICE.

EMIL KORSETZ, OF MILWAUKEE, WISCONSIN.

RECEPTACLE.

Application filed September 11, 1926. Serial No. 134,897.

This invention relates to improvements in receptacles, designed for the reception of smokers' waste, expectoration and the like.

It is one of the objects of the present invention to provide a depository of the class described which will further cleanliness and sanitation.

A further object of the invention is to provide a receptacle which will eliminate the unsanitary conditions incident to open receptacles for expectoration and will also eliminate odors issuing from the same due to the collection of smokers' waste and refuse.

15 A further object of the invention is to provide a receptacle of the class described which is attractive and ornamental in appearance and so constructed and inscribed as to invite proper use of the same.

20 A further object of the invention is to provide a receptacle combining a cuspidor and a smoker's waste receiver and so constructed that the different receivers may be readily and quickly detached for emptying and cleaning.

25 A further object of the invention is to provide a receptacle of the class described which is of very simple construction, is easily operated, is strong and durable, and is well adapted for the purposes described.

30 With the above and other objects in view, the invention consists of the improved receptacle, and its parts and combinations as set forth in the claims and all equivalents thereof.

35 In the accompanying drawing in which the same reference characters indicate the same parts in all of the views:

40 Fig. 1 is a side view of the improved receptacle;

45 Fig. 2 is a vertical sectional view thereof, taken on line 2—2 of Fig. 3;

50 Fig. 3 is a plan view, parts being broken away and shown in section; and

55 Fig. 4 is a rear view.

Referring now more particularly to the drawings, it will appear that the numeral 8 indicates a flat rectangular base plate, preferably formed of polished metal. A vertical partition or support 9, which is flanged at its lower edge portion, is screwed to the base plate and the upper end portion of the support 9 is provided with a slot 10.

An auxiliary container member 11, preferably of polished metal, and having an open upper end, is stationed on the base plate

8 rearwardly of and adjacent the support 9. The rear face of the container 11, at its upper end portion, is provided with a hooking flange 12 to engage the slot 10 of the support 9 whereby the auxiliary container 11 is detachably secured to the support 9.

Extending from the forward face of the support 9 is a bracket 13 to which a semi-circular arm 14 is secured. Another complementary semi-circular arm 15 is hinged to the bracket 13, and is adapted to overlap at its free end the free end of the fixed arm 14.

A cuspidor member or main container 16 is stationed on the medial portion of the base plate 8, said cuspidor preferably being formed of glass with suitable instructive indicia thereon. The neck portion of the cuspidor is embraced by the arms 14 and 15 to 70 removably hold the cuspidor in position, the hinged arm 15 being locked in engaging position by means of a pin 17 projecting from the end portion of the fixed arm 14 and engaging an aperture in the hinged arm 15. 75 Thus, when the arm 15 is pressed to disengage the pin from its aperture, and swung to the dotted line position shown in Fig. 3, the cuspidor may be readily removed for cleaning purposes. 85

The top of the cuspidor member is normally closed by means of a lid 18 pivotally connected at its rear to a pair of bearing flanges 19 extending from the upper portion of the support 9. The lid 18 is formed of 90 a plurality of layers including a bottom layer 20 of circular form and constituting the entire bottom of the lid, said bottom layer 20 being preferably composed of celluloid. An explanatory or instructive word 95 21 is delineated on the forward half of the celluloid. The lid member is divided into halves by means of a tray 22 having a bottom portion 23 of non-inflammable material covering the rear half of the bottom layer 20 100 and protecting it against burning. The bottom portion of the tray may have suitable lettering 24 thereon to indicate the purpose of the tray. The forward half of the celluloid bottom 20 is covered and protected by 105 a sheet of mica 25 or other similar transparent and non-inflammable material.

It will be noted that the tray 22 is formed with sides 26, open at the rear, as at 27, and depending from the front side portion 110 28 is a curved and inclined plate or chute 28. Secured to the rear portion of the tray sides

is a spout or hood member 29 to direct material toward the opening 27 and to prevent it from falling in an unauthorized direction from the tray when the entire lid is pivoted, as shown in dotted lines in Fig. 1.

5 The mechanism for pivoting the lid and tray includes a foot pedal 30 positioned at the side portion of the base plate and inclined with relation thereto, the lower end 10 portion of the pedal being hinged to the plate, as at 31. Also, a spring steel member 32 underlies the pedal to yieldingly hold it in its "up" position. The top of the pedal may be covered with corrugated rubber 33 or other material to prevent slipping.

15 The foot pedal 30 is connected with the lid member 18 to actuate it, by means of a vertical rod 34 slidably mounted medially in brackets 35 extending from the side of 20 the vertical support 9. The lower end portion of the rod 34 is bent right angularly and is secured in a bracket 36 at the free end portion of the pedal. The upper end portion of the rod 34 is also bent angularly 25 and enters an elongated aperture 37 in the side portion of the tray. Hence, when the foot pedal is pushed downwardly, the lid member will be pivoted to open position by means of motion transmitted through the 30 rod 34. The spring 32 will automatically return the pedal and lid to normal position when pressure on the pedal is released.

It should also be observed that the bearing members 19 are formed with forwardly 35 projecting arm portions 38 extending slightly above the plane of the top of the cuspidor, and when the lid is dropped to normal closing position, said arm portions will serve to cushion the jar of the lid on the cuspidor.

40 The improved receptacle is adapted to be used where cuspidors and ash receivers are now found, and will eliminate the unsanitary and objectionable features of former devices for the same purposes. The lid member 18 will always close the cuspidor member and keep flies and insects therefrom. It is proposed that ashes, waste, and cigar and cigarette stubs be deposited in 45 the tray portion of the lid, the curved plate 50 28 assisting in guiding the same into the tray when thrown. They will then remain on the tray until the lid is pivoted by means of the foot pedal, and when the lid is so pivoted, the refuse will be guided and dumped through the opening 27, by means 55 of the hood 29, into the auxiliary container 11. The auxiliary container may, of course, be easily removed and emptied periodically. When one desires to expectorate, the cuspidor member should be used for that purpose, and access thereto is gained by pressing the foot pedal to raise the lid. The contents 60 of the cuspidor may be deodorized through the use of certain suitable chemicals contained therein. As previously explained, 65

the cuspidor may be readily detached for emptying and cleaning.

From the foregoing description, it will be seen that the improved receptacle will further sanitation and cleanliness, and is of 70 very simple and novel construction, and is well adapted for the purposes set forth.

What I claim as my invention is:

1. A receptacle, comprising a main container, a lid hinged thereto, and an auxiliary 75 container to receive deposits from the lid when the same is raised.

2. A receptacle, comprising a main container, a lid hinged thereto, mechanism connected with said lid for moving it, and an auxiliary 80 container to receive deposits from the lid when the same is moved.

3. A receptacle, comprising a main container, a normally horizontal lid therefor, the rear portion of said lid being formed as a 85 tray, and an auxiliary container adapted to receive deposits from said tray.

4. A receptacle, comprising a main container, a lid therefor, a tray mounted on said lid and having a side opening, and an auxiliary 90 container adjacent the main container to receive deposits from the tray through the opening thereof.

5. A receptacle, comprising a main container, a lid pivoted thereto, a tray covering 95 a portion of said lid and having a side opening, and an auxiliary container adjacent the main container to receive deposits through the side opening of the tray when the lid is raised.

6. A receptacle, comprising a main container, a lid pivoted thereto, a tray covering a portion of said lid, an apertured hood for said tray, and an auxiliary container adjacent the main container to receive deposits 100 discharged through said hood when the lid is moved.

7. A receptacle, comprising a flat base member, a main receptacle removably mounted thereon, a normally horizontal lid 110 for said main receptacle, and an auxiliary container removably mounted on the base member and adapted to receive deposits from said lid when the same is tilted.

8. A receptacle, comprising a base member, a pair of arms connected thereto, a main receptacle stationed on the base member and removably engaged by said arms, a lid for said main receptacle, and an auxiliary container removably mounted on the base member and adapted to receive deposits from said lid.

9. A receptacle, comprising a base member, an arm rigidly connected thereto, a complementary arm hinged to the base member and releasably engageable with said first mentioned arm, a main receptacle stationed on the base member and embraced by said arms, a lid for said main receptacle, and an auxiliary container removably mounted on 125 130

the base member and adapted to receive deposits from said lid.

10. A receptacle, comprising a base plate, a vertical support mounted thereon, a pair of arms carried by said support, a main container stationed on the base plate and removably engaged by said arms, a pivotally mounted lid for said main container, and an auxiliary container detachably held by said support and adapted to receive deposits from said lid.

11. A receptacle, comprising a base plate, a vertical support mounted thereon, an arm rigidly carried by said support, a complementary arm hinged to the support and releasably engageable with said first mentioned arm, a main container stationed on the base member and releasably embraced by said

arms, a pivotally mounted lid for said main container, a tray covering a portion of said lid, an apertured hood for said tray, an auxiliary container detachably hooked to said support to receive deposits through said hood when the lid is pivoted, and a foot pedal connected with said lid for pivoting the same.

12. In combination, a receptacle, a support thereadjacent, a cover hinged to the support and adapted to close the receptacle, and an arm extending horizontally from the support and slightly above the plane of the top of the receptacle to cushion the jar of the cover when the same is moved to closing position.

In testimony whereof, I affix my signature.
EMIL KÖRSETZ.
